United States Patent Office.

OTIS B. BARTLETT, OF LEWISTON, MAINE.

Letters Patent No. 90,983, dated June 8, 1869.

IMPROVEMENT IN STOVE-COVERS.

The Schedule referred to in these Letters Patent and making part of the same.

To all whom it may concern:

Be it known that I, OTIS B. BARTLETT, of Lewiston, in the county of Androscoggin, and State of Maine, have invented a new and improved Stove-Cover; and I do hereby declare that the following is a full and exact description of the same, reference being had to the accompanying drawings, and to the letters of reference marked thereon.

This invention relates to an improved stove-cover, and consists mainly in the employment of mica, or other similar material, in connection with a stove-cover; it consists also in a special form and construction, which will be fully described hereinafter.

In the drawings—

Figure 1 is a perspective view of an ordinary stove, with my invention attached.

Figure 2, a plan view of my invention inverted.

Figures 3 and 4, sectional views through lines $x-x$ and $y-y$, fig. 2.

To enable others skilled in the art to which my invention belongs, to make and use the same, I will proceed to describe fully its construction and operation.

A represents a stove-cover, provided with the circular rim a , which is constructed of proper size and shape to fit accurately the stove-opening.

It has also the ribs b , which, extending slightly upward, unite in the centre, and form a band for the handle c .

The lower sides of the ribs are provided with a pro-

jection, b' , by means of which a socket is formed for the mica.

d represent sashes or frames, which fit snugly into the sockets formed by the rim and ribs, as shown.

e represent ears, extending below the ribs b , which are provided with openings, through which pins are passed to secure the frames d in place. Other forms, of course, will suggest themselves.

By thus providing a cover with mica, the room is made more cheerful, and the condition of the fire can be easily seen.

The special construction shown by its conical form, permits more heat to escape into the apartment than is ordinarily the case.

I am well aware that mica has been used in stove-doors, and I do not claim its use in itself, but

What I claim, and desire to secure by Letters Patent of the United States, is—

1. A stove-cover, when provided with mica, substantially as described.

2. The cover A, of the form shown, when constructed substantially as described for the purpose set forth.

This specification signed and witnessed, this 1st day of December, 1868.

OTIS B. BARTLETT.
